UNITED STATES PATENT OFFICE.

OLIVER B. SHALLENBERGER, OF ROCHESTER, ASSIGNOR TO THE WESTINGHOUSE ELECTRIC COMPANY, OF PITTSBURG, PENNSYLVANIA.

INDICATOR FOR ELECTRIC CIRCUITS.

SPECIFICATION forming part of Letters Patent No. 394,728, dated December 18, 1888.

Application filed October 11, 1888. Serial No. 287,846. (No model.)

To all whom it may concern:

Be it known that I, OLIVER B. SHALLENBERGER, a citizen of the United States, residing in Rochester, in the county of Beaver 5 and State of Pennsylvania, have invented certain new and useful Improvements in Indicators for Electric Circuits, (Case No. 224), of which the following is a specification.

The invention relates to the construction 10 of meters for indicating the difference of potential or the current flowing upon an electric circuit.

The object of the invention is to provide an indicator of this character in which the 15 variations in the pull exerted shall be directly proportional to the variations in current flowing through a very wide range of movement.

The invention consists in so organizing two 20 solenoids and their respective cores that when one core is in a position to be acted upon by its solenoid with a maximum effect the other core is approaching a corresponding position with reference to its solenoid, and as the first 25 core passes beyond the point of maximum effect the second core reaches its position of maximum effect, so that the increase of attraction upon one core will compensate for the decrease of attraction upon the other 30 core.

In the accompanying drawings, Figure 1 is a theoretical diagram designed to illustrate the variations in the attraction exerted upon the two cores in the different positions which 35 they may bear with reference to their magnetizing-solenoids, and Fig. 2 is a diagram illustrating apparatus for carrying out the invention.

It is well known that when a core is moved 40 into and out of a solenoid traversed by an electric current the degree of attraction or pull exerted differs according to the different positions occupied by the core. Thus if the core is extended entirely through the solen- 45 oid it is in a position of equilibrium and no pull is exerted; but as it is gradually withdrawn the pull increases gradually to a maximum. It then remains approximately constant through a certain distance, and afterward 50 gradually decreases until the core is entirely removed from the magnetic field of the solen-

oid. If a spring or weight is employed to oppose the pull of the solenoid and the current through the solenoid is gradually diminished, the core will be gradually withdrawn 55 from the solenoid; but the position in which it will be most sensitive to a given decrease of current is that in which the pull remains nearly constant over a considerable distance for a given current, and this position corresponds to that in which the maximum pull is exerted. In other positions it will respond much less readily to a given change of current.

In the diagram, Fig. 1, let the verticles x' 60 x^2 x^3 , drawn from the normal N N , represent different positions of a core in a solenoid, and the curved line c' the value of the attraction exerted upon it in the different positions. When the core extends through the 65 solenoid or is in a position of equilibrium, the line c' touches the normal N at x . Then as the core is withdrawn the line c' rises from the normal and attains a maximum at x^2 . As the core is further withdrawn, the line c' again 70 approaches the normal and touches it at x^3 , at which point the core is practically removed from the field of the solenoid. Now it is evident that the position of greatest sensitivity lies between the lines x' and x^3 , 75 where the maximum pull is exerted. In practice, therefore, it has been customary to so construct electric indicators as to utilize the movements of the core through only this portion of the field when accurate measurement is required. If the current is such as to bring the core outside of these limits, a given variation in the current will have a much less effect upon the core. If, now, a second solenoid and its core be so related 80 to the one just described that it is brought into action at the time the pull upon the first core commences to diminish, then its curve of pull may be represented by the line c^2 , which is in every respect similar to the 85 line c' , except in its location upon the normal N N . The sum of these two curves is represented by the dotted line c . If, therefore, the two cores be secured to a common support, the line c will represent the resultant pull exerted upon that support, and it is evident that 90 the range of sensitiveness is prolonged from 95 100

the line x' to the line y' , and that between the lines x^2 and y^2 the degree of pull exerted is approximately constant, and if the motion be opposed by a spring the movement of the support will be approximately proportional to the variation in the current.

Referring now to Fig. 2, let $A' A^2$ represent two solenoids, which are in this instance included in series in a conductor, L , between points 1 and 2 in an electric circuit. They may, however, be connected in multiple arc. The solenoids are respectively provided with soft-iron cores $a' a^2$, which may with advantage be composed of magnetically-separated soft-iron wires, especially so in case the indicator is to be used with alternating electric currents. The cores here shown are supported at the respective ends of a pivoted beam, B , and they are curved in such a manner as to enter their respective solenoids when the beam is turned upon its axis b in the proper direction. A refractile spring, s , and adjusting device s' , or their equivalents, are employed to oppose the attraction of the solenoids. The two cores are so located with reference to each other and their respective solenoids that the curves of their attractions correspond to the lines c' and c^2 , Fig. 1—that is to say, as the core a' is passing through the position of maximum magnetic effect with reference to the solenoid A' the core a^2 is approaching a corresponding position with reference to the solenoid A^2 . The effect of this is to cause the variation in the resultant pull exerted upon the beam B to be approximately constant for every given increase or decrease of current flowing through the solenoids between certain limits of position, and there is also an equal sensitiveness on the part of the

instrument between such limits of movement 40 as will be clearly understood in connection with the description of Fig. 1.

An indicator, C , and scale D may be employed for showing the position of the support B and the respective cores.

I claim as my invention—

1. An indicator for electric currents, consisting of the combination of two assisting solenoids, cores respectively applied thereto, said cores being so located with reference to 50 their solenoids that one enters and passes through a position of maximum attraction with reference to its solenoid while the other is approaching and entering the position of maximum attraction with reference to its 55 solenoid, and an indicator actuated by the movements of the cores.

2. An indicator for electric currents, consisting of assisting solenoids connected in an electric circuit, two cores respectively applied 60 thereto, a support common to both cores, and an indicator actuated thereby, one of said cores normally projecting into its solenoid a greater distance than the other.

3. In an indicator for electric circuits, two 65 solenoids and two cores respectively actuated by said solenoids, one of said cores being normally situated in a position of greater magnetic attraction than the other with reference to its solenoid.

In testimony whereof I have hereunto subscribed my name this 2d day of October, A. D. 1888.

OLIVER B. SHALLENBERGER.
